ATTORNEYS

UNITED STATES PATENT OFFICE.

ALBERT H. ROETH, OF NEW YORK, N. Y.

BUILDING TILE.

Application filed September 29, 1921. Serial No. 504,057.

To all whom it may concern:

Be it known that I, ALBERT H. ROETH, a citizen of the United States, and a resident of the city of New York, borough of the Bronx, in the county of Bronx and State of New York, have invented a new and Improved Building Tile, of which the following is a full, clear, and exact description.

This invention relates to improvements in building tiles, an object of the invention being to provide an interlocking tile provided with both vertical and horizontal air spaces which will effectively prevent moisture from seeping through a wall.

15 A further object is to provide building tiles which, when arranged in tiers, will provide vertical and horizontal passages through the tiers and from the top to the bottom of a wall.

20 Still another object is to provide an interlocking damp-resisting building tile in which air spaces are provided between every mortar joint so that if the outside joint absorbs moisture, there is no danger 25 of the moisture seeping through the wall.

With these and other objects in view, the invention consists in certain novel features of construction, combinations and arrangements of parts, as will be more fully 30 hereinafter described and pointed out in the claims.

In the accompanying drawings—

Figure 1 is a perspective view of one of my improved tiles.

35 Figure 2 is an end view showing two of the tiles in super-imposed relationship.

Figure 3 is a fragmentary top plan view partly shown in section showing the manner in which the tiles interlock.

40 Referring in detail to the drawings, my improved building tile comprises a pair of outside walls 1 and 2 and a pair of inner walls 3 and 4. Integral webs 5 spaced from the ends of the walls connect the outer and

45 inner walls. These webs terminate short of the upper and lower edges of the walls to provide horizontal air spaces such as 6 when the tiles are arranged in super-imposed relationship.

50 It will also be noted that the webs 5 are spaced a considerable distance apart to provide vertical air passages 7 between the inner and outer walls of the tile. The two inner walls 3 and 4 are connected by integral webs such as 8. It will be seen that

the webs 8 terminate short of the upper edges of the inner walls and extend appreciably below the lower edges of the inner walls. It is to be noted, however, that the distance between the top of the webs 8 and the upper edges of the walls 3 and 4 is greater than the distance between the bottom of the webs 8 and the bottoms of the walls 3 and 4. By virtue of this construction, an additional horizontal air space, such as 9, is provided between the two inner walls when the tiles are arranged one upon the other.

Dove-tailed grooves are formed by co-acting recesses 10 in one end of each of the walls 3 and 4. These grooves interlock with tenons 11 at the other ends of the walls 3 and 4 in an adjacent tile.

When the tiles are laid the mortar is placed upon the upper surfaces of all of the walls as indicated at 12 and is also applied to the ends of all of the walls as indicated at 13 so that the tiles are completely encircled by four spaced mortar joints. Each mortar joint is separated from adjacent joints by both horizontal and vertical air spaces, hereinbefore described, and there is but slight chance of moisture seeping from one joint to the next one.

Although I have shown and described a building tile formed of a single piece of material by any approved and well known method, it will be apparent that interlocking building blocks might embody the same novel features as the illustrated tile. Various slight changes and alterations might be made in the general form and arrangement of the parts described, without departing from the invention and hence I do not wish to limit myself to precise details set forth, but shall consider myself at liberty to make such slight changes and alterations as fairly fall within the spirit and scope of the appended claims.

What I claim is:—

1. A building tile, comprising a pair of inner walls connected by webs, a pair of outer walls connected to the inner walls by webs, the webs being spaced from the ends and terminating short of the upper and lower edges of the walls, said inner walls having grooves formed in their inner faces at one end forming a dovetail groove, and grooves formed in their outer faces at the other end forming a tenon.

100

105

110

2. A building tile, comprising a pair of inner walls spaced apart and connected by webs, a pair of outer walls connected to the inner walls by webs, said inner walls projecting beyond the outer walls at one end and having grooves cut in their outer faces forming a tenon on the extended end and grooves cut in their inner faces at the other end forming a dovetail slot, the said webs being spaced from the ends of the walls and terminating short of the upper and lower edges of the walls providing horizontal air passages. 10
ALBERT H. ROETH.
